UNITED STATES PATENT OFFICE.

PAULINE ROSENFIELD, OF NEW YORK, N. Y., ASSIGNOR TO MEYER LEHMAN, OF NEW YORK, N. Y.

FLEXIBLE SUPPORT FOR HAT-TRIMMINGS.

1,186,838.

Specification of Letters Patent. Patented June 13, 1916.

Application filed March 15, 1916. Serial No. 84,324.

To all whom it may concern:

Be it known that I, PAULINE ROSENFIELD, a subject of the Czar of Russia, and a resident of the city of New York borough of Bronx, in the county of Bronx and State of New York, have invented a new and Improved Flexible Support for Hat-Trim-
5 mings, of which the following is a full, clear, and exact description.

10 My invention relates to a flexible support particularly adapted for the shaping of bows; and the object thereof is to provide a simple and inexpensive ribbonlike support which is reinforced or strengthened at the 15 longitudinal edges so that when the same is shaped, with any suitable material, into a bow or similar ornament it will prevent the material from sagging at the edges and will allow sufficient deformation to adjust the 20 shape of the ornament.

With the above and other objects in view, the nature of which will more fully appear as the description proceeds, the invention consists in the novel construction, combination 25 and arrangement of parts as herein fully described, illustrated and claimed.

In the accompanying drawings, forming part of the application, similar characters of reference indicate corresponding parts in 30 all the views.

Figure 1 is an elevation of an ornament in the shape of a bow provided with an embodiment of my invention; Fig. 2 is an elevation of a fragment of the support; and 35 Fig. 3 is a cross section on line 3—3, Fig. 2.

Referring to the drawings, 4 is a strip of crinoline bordered at each longitudinal edge with a wired tape 5, both tapes being pref-

erably provided on the same surface of the crinoline. The wired tape 5 reinforces the 40 crinoline and gives body to the same at the edges, whereby a bow 6 formed of ribbon inclosing the support will retain any desired shape. The wired support also prevents the parts 1 of ribbon overhanging the edges 45 of the support from sagging, due to the strength of the support at the edges.

A bow or ornament inclosing a support as described makes the ornament flexible and will easily permit an adjustment in the 50 ornament without the necessity of taking the same apart. The material forming the ornament does not have to be stitched to the support, for the wired tapes at the edges prevent the material of the ornament from 55 sliding off the support. A shaped bow or other ornament can be easily reshaped without a change of support, for the support can be as easily reshaped as the material of which the ornament is formed. 60

I claim:

1. A support of the class described formed of a strip of a crinoline reinforced by wired tape at the longitudinal edges thereof.

2. A support of the class described comprising a crinoline strip and wired tape secured to the crinoline at the longitudinal edges and on the same surface of the strip.

In testimony whereof I have signed my name to this specification in the presence of 70 two subscribing witnesses.

PAULINE ROSENFIELD.

Witnesses:

MEYER LEHMAN,
B. JAFFE.
